The ornamental design for a scoop holder, as shown and described.

DESCRIPTION

FIG. 1 is a front perspective view of a scoop holder according to my new design;

FIG. 2 is a front elevation view thereof;

FIG. 3 is a rear elevation view thereof;

FIG. 4 is an end view thereof;

FIG. 5 is an opposite end view thereof;

FIG. 6 is a top plan view thereof;

FIG. 7 is a bottom plan view thereof; and,

FIG. 8 is an exploded front perspective view thereof.

The broken lines shown in FIGS. 1-8 depict portions of the scoop holder that form no part of the claimed design.
